Fig. 3.

Fig. 4.

Fig. 5.

Fig. 6.

Fig. 7.

FIG. 1 is a perspective view of a food and beverage service device for changing the temperature of food and beverage containers and their contents showing my new design.

FIG. 2 is a side view of the embodiment shown in FIG. 1;

FIG. 3 is a top plan view of the embodiment shown in FIG. 1;

FIG. 4 is a bottom plan view of the embodiment shown in FIG. 1;

FIG. 5 is a perspective view of another embodiment of the device shown in FIG. 1;

FIG. 6 is a top plan view of the embodiment shown in FIG. 5; and

FIG. 7 is a side view of the embodiment shown in FIG. 5;

I claim:

The ornamental design for a food and beverage service device for changing the temperature of food and beverage containers and their contents, as shown and described.
